UNITED STATES PATENT OFFICE.

THOMAS W. L. MCGUIRE, OF KANSAS CITY, MISSOURI.

CARBURETOR.

Application filed July 18, 1917. Serial No. 181,260.

To all whom it may concern:

Be it known that I, THOMAS W. L. MCGUIRE, a citizen of the United States, residing at Kansas City, in the county of Jackson and State of Missouri, have invented certain new and useful Improvements in Carburetors, of which the following is a specification.

My invention relates to new and useful improvements in carburetors for explosive engines, and more particularly to that type of construction in which the amount of air admitted to the mixing chamber of the carburetor is automatically proportioned relative to the suction created in such mixing chamber by the engine, thus as the speed of the engine increases or diminishes the supply of volatilized fuel is proportionally increased or diminished.

In carrying out the invention, I employ a number of perforated disks in the mixing chamber of the carburetor. Said disks are fixedly-mounted upon a shaft driven by a fan, which in turn is controlled by the suction of the engine. As the disks revolve they carry up hydrocarbon oils into an air space in the mixing chamber, where they are subjected to a stream of air passing through said mixing chamber, to the end that they are volatilized and pass in this state into the engine.

While the carburetor may be used to advantage on different types of explosive engines, it is particularly efficient when used in connection with the multicylinders of an automobile engine and is adapted to supply the same with volatilized fuel, irrespective of the angle it may assume in going up or down hill, or whether its intake manifold be arranged at a higher or lower level than the carburetor.

Other objects will hereinafter appear as the invention is described in connection with the accompanying drawings, in which:

Fig. 1 is an end elevation of the carburetor connected to a multicylinder engine.

Fig. 2 is a cross section, enlarged, on line II-II of Fig. 4.

Fig. 3 is an enlarged, vertical section of a check valve employed in carrying out the invention.

Fig. 4 is a longitudinal, sectional view of the carburetor, on line IV-IV of Fig. 1.

Fig. 5 is a cross section on line V-V of Fig. 4.

Fig. 6 is a cross section on line VI-VI of Fig. 4.

Fig. 7 is a vertical section on line VII-VII of Fig. 6.

Fig. 8 is a vertical section on line VIII-VIII of Fig. 7.

In carrying out the invention, I employ a container 1 which may be located at the rear of the automobile in lieu of the gasoline tank usually employed. Said container 1 has a centrally-disposed mixing chamber 2 divided into three compartments 3, 4 and 5, by partitions 6 and 7, which extend only part way to the top of the chamber 2 to leave passageways 9 and 10 for the flow of air and fuel mixtures, as will hereinafter appear.

An air intake 14 communicates with the upper portion of the mixing chamber 2, which has outlet ports 15 and 16 at its opposite ends communicating with an outlet duct 18, which communicates at one end with a port 20 leading into a chamber 22, containing a suction fan 23. Access is had to the duct 18 and the ports 15, 16 and 20, through a removable cover 24 secured to the upper portion of the mixing chamber 2.

The suction fan 23 is fixedly-mounted upon a centrally-disposed shaft 25, extending longitudinally through the mixing chamber 2 and journaled in a bearing 27, fixed to one end of said mixing chamber 2, and in bearings 29 and 30 carried by the partitions 6 and 7, respectively. Said shaft 25 is also journaled in a stuffing box 32, secured to an end wall of the compartment 5 to prevent the fluid therein from flowing into the fan chamber 22. One end of the shaft 25 projects through the outer wall of the fan chamber 22 (Fig. 4), and terminates in a rectangular portion 35, to receive a crank (not shown) whereby it may be initially rotated to obtain a supply of volatilized fuel to start the engine.

Within compartments 3, 4 and 5 of the mixing chamber 2 are perforated disks 37 and 38, which, as they revolve, carry the fluid or fluids in said compartments up into the air space above the level of such fluids, where they are volatilized by the incoming air

which enters the intake 14 and escape through the outlet ports 15 and 16. The disks 38 embody wire or other suitable fabric which takes up more of the fuel than the smooth sides of the disks 37.

The mixing chamber 2 receives fluid from oppositely-disposed supply chambers 40 and 41 closed at the top with covers 40^a and 41^a, respectively. Chamber 40 is divided into three compartments by partitions 42 and 43, and chamber 41 is divided into three compartments by partitions 44 and 45. The compartments of chamber 40 communicate with the compartments 3, 4 and 5 of the mixing chamber 2 through ports 46, and the compartments of chamber 41 communicate with said mixing chamber compartments through ports 47. In practice the number of compartments may be increased or diminished as preferred. Fluid is introduced in the compartments of chamber 41 through inlets 48 normally closed by caps 49, to exclude dust and other foreign matter. Drain cocks 50 leading from the bottom of the chamber 41 are provided for draining off the fluid and any accumulation of sediment.

51 designates a fuel mixture storage receptacle arranged above the chamber 40 for reserving a supply of fuel mixture from the mixing chamber 2. Fuel mixture is introduced into said storage receptacle 51 through a branch duct 52, communicating with a main duct 54, leading from the fan chamber 22 to the intake manifold A, of the engine B, to which it is connected by a check valve 55, which prevents the fuel mixture from flowing backward from the manifold into said main duct 54.

40 A manually-controlled valve 57 is coupled to the main duct 54 to shut off the flow of fuel mixture therethrough to the manifold A, when it is desired to stop the engine. A deflector 60 extends into the main duct 54 where it communicates with the branch duct 52, for the purpose of deflecting a portion of the fuel mixture upwardly into the receptacle 51 through said branch duct 52. A check valve 63 is provided where the branch duct 52 enters the receptacle 51, to prevent the fuel mixture therein from flowing backwardly into said duct. An outlet duct 65 leads from the receptacle 51 to a manifold 66, for introducing fuel mixture directly into the combustion chambers of the cylinders of the motor when cranked for the purpose of starting the same. Said outlet duct 65 has a valve 68, for controlling the flow of fuel mixture therethrough.

60 In practice, the container 1 is supplied with fluid to a level below the top of the partitions 6 and 7, so that it will not splash from one compartment to another in the mixing chamber 2. The partitions 42 and 43 in the chamber 40, and the partitions 44

and 45 in the chamber 41, prevent the fluid from splashing about therein unduly or rushing from one end of said chambers to the other while the automobile is in motion and traveling over uneven ground. 70 Said partitions 42 and 45, inclusive, are also important in that they prevent the fluid in one compartment intermixing with the fluid in another compartment when different fluids are used, as I have found by practice 75 that three different fluids such as gasoline, kerosene and water can be used both efficiently and economically in the production of a carbureted mixture for driving the engine. However, I do not restrict myself to 80 the use of any particular kind or number of fluids. After the several compartments have been supplied with fluid, the carbureted mixture is initially produced by manually cranking the shaft 25, which operation rotates the disks 37 and 38, causing them to carry the fluid in the mixing chamber 2 upwardly into the air space therein, where it is formed into said carbureted mixture by 85 a current of air drawn into the intake 14 by the suction fan 23. As the carbureted mixture is formed it is drawn into the combustion chambers of the motor B, and exploded in the usual way to start and drive said motor B. Before the motor is cranked the 90 valve 68 is closed, so that a portion of the carbureted mixture may flow through the duct 52 and accumulate in the receptacle 51.

When the engine is running the suction created thereby rotates the fan 23, which 100 in turn drives the shaft 25 with the disks 37 and 38.

From the foregoing description it is apparent that I have produced a carburetor embodying the advantages above enumerated, and while I have shown and described the preferred form of said carburetor, I reserve the right to make such changes in the construction, combination, and arrangement of parts as properly fall within the 110 spirit and scope of the appended claim.

Having thus described my invention, what I claim and desire to secure by Letters Patent, is:

In a carburetor, a liquid fuel mixing chamber having an air space, rotary elements mounted in said mixing chamber to carry a portion of the fuel upwardly into the air space at each revolution to produce a fuel mixture, a duct leading from said mixing chamber, partitions dividing the mixing chamber in said carburetor into compartments, a supply chamber, and partitions dividing said supply chamber into compartments which communicate with the mixing chamber compartments to supply the same with different kinds of fuel.

In testimony whereof I affix my signature.

THOMAS W. L. McGuIRE.
